Application August 12, 1941, Serial No. 406,558

3 Claims. (Cl. 226—129)

The present invention relates to supporting structures of beverage filling machines.

Machines for filling containers with carbonated beverages, including beer, ordinarily comprise a base to which a stationary table is fixed and a rotary filling structure mounted for rotation on the base. The rotary filling structure includes a hollow central shaft and journal structure which supports a filling table spaced above the stationary base and the central journal also supports a superstructure which carries the filling heads and a central liquid reservoir. The superstructure is positioned some distance above the filling table. Containers to be filled are moved from the stationary table to container supporting platforms which are vertically reciprocable in the filling table so that they will force a container upwardly against a filling head on the superstructure so that flow may occur from the reservoir to the container.

It is most important that the mouth of each container be held firmly sealed against the corresponding filling head in order that proper filling may be accomplished and the platform lifting means is, therefore, moved upwardly with considerable force or pressure. For this reason, the superstructure, comprising the filling reservoir and the associated filling heads, must be firmly held against lifting movement. However, it is not practicable to so construct a filling machine that the superstructure will be permanently and rigidly secured to the filling table, since the superstructure must be vertically adjustable with respect to the filling table in order to permit various sizes of containers to be handled upon the machine.

It has been found that the upward movement of containers against the filling heads tends to lift the superstructure or at least tilt it with respect to the filling table. The tendency toward tilting occurs by reason of the fact that as the filling structure rotates, the container supporting platforms are lowered so that containers may be removed therefrom and empty containers placed upon the platforms. Thus, throughout a continually changing portion of the superstructure, i. e., the portion which is moving past the stationary table, no upward pressure is exerted upon the superstructure while at the same instant upward pressure is being exerted upon the remainder of the superstructure by the raised containers.

It will be observed that the pressure discussed above as exerted upwardly against the superstructure is also simultaneously exerted downwardly

upon continually changing portions of the edge of the filling table.

Another problem peculiar to machines for filling carbonated beverages results from the fact that the beverage to be flowed into the containers is under pressure, since the filling tank is ordinarily subject to the same pressure as the carbonator or beer vats. This pressure, therefore, exerts a bodily lifting action upon the superstructure.

The present construction includes telescopic rigid elements, for example, screw jacks, extending between the filling table and the superstructure and positioned at points radially spaced from the axis of the filling structure. This arrangement insures that the superstructure may be readily adjusted with respect to the filling table by a positive raising or lowering action, and further insures that the superstructure will be securely held against tilting or bodily lifting with respect to the filling table.

Most types of beverage filling machines have the superstructure and filling table connected by centrally positioned telescoping shafts so connected that the superstructure can readily be raised, the telescopic connection being such that rotary driving movement will be imparted to the superstructure from the filling table. Furthermore, the vertical adjustment is obtained either by rotating the superstructure with respect to the filling table to take advantage of a threaded connection between the two, or by rotating a threaded element about the lower portion of the shaft to vertically move the superstructure.

The above arrangements are not of optimum efficiency because the superstructure is only connected to the filling table at a central point, and tilting of the superstructure therefore cannot be entirely eliminated, particularly with a superstructure of large diameter. Because the superstructure is usually only held in the desired vertical position by a frictional locking means, which an operator may fail to secure, bodily lifting of the filling table by gas pressure alone can also occur.

It has been heretofore proposed, in non-beverage fillers, to support containers or reservoirs above filling tables at spaced points, but in such installations the reservoirs have simply been tanks of small diameter at a minimum distance above the filling table, the principal reason for spacing the supports being to provide a plurality of posts to carry the load of the material in the reservoir.

In a large beverage filler, on the other hand,

the superstructure may have a diameter of from five to ten feet, which must be mounted about two feet above the filling table on a central shaft having a diameter of about eight inches. It will therefore be understood that the problem in large beverage fillers is not so much to simply support weight as to support a body of large area at a substantial height in such a way that it cannot tilt and cannot be lifted by gas pressure.

It has also been proposed to brace the superstructure to a filling table at points radially spaced from the vertical axis of the filling structure by means of non-rigid elements, but these arrangements have not obviated all difficulties; are extremely involved from a mechanical standpoint, and require careful operation to prevent straining the superstructure. Furthermore, such prior arrangements have ordinarily involved imparting rotational movement from the filling table to the superstructure through the connecting means. In view of the fact that the connecting means are usually spaced radially some distance from the vertical axis of the filling structure, a twisting moment can readily occur with these prior arrangements, particularly if the machine is of a high speed type.

Another object of the present invention is to provide a superstructure support for beverage filling machines which is of such construction that the superstructure will be positively rotated from the filling table without twisting or other play between the two, and which is of simple design.

A still further object of the invention is to have the supporting arrangement of such design that the supporting elements can be operated simultaneously and readily to move the superstructure vertically with respect to the filling table so as to enable containers of different sizes to be handled.

The arrangement described in the preceding paragraph is highly desirable in that it eliminates the tilting strains which occur if the connecting elements are individually operable.

Still another object of the invention is to provide an automatically operable locking device for the adjusting mechanism.

By the locking arrangement just described, it will not be possible for relative movement to occur, as may be the case with prior machines wherein the operator must finally set a locking device.

A further important object of the invention is to provide means to maintain a filling table against tilting action. By combining such an arrangement with bracing means between the filling table and superstructure, the latter can be more securely held against tilting.

As has been stated above, filling tables are supported upon the central hollow shaft of rotary filling structure at some distance above the base of the machine. The filling table, like the superstructure, may have a diameter of from five to ten feet and it is provided at its rim with fairly heavy bottle supporting platforms and guides or cylinders vertically movable through a distance of approximately eighteen inches to lift containers to the filling heads. Thus the filling table is always having downward pressure exerted upon continually changing portions of its edge by the forces holding the bottles in contact with the filling heads. In addition, the vertical shifting of the filling platforms exerts some force toward giving the filling table a tilting movement.

The present invention contemplates providing

vertical bracing elements upon the machine base which engage the edge portion of the under surface of the filling table to prevent the latter from tilting. The bracing elements are circumferentially spaced with respect to the filling table and preferably comprise standards having rollers journalled in their upper ends to engage a circular track on the lower surface of the filling table.

10 By the arrangement just described, the filling table will be held against all tilting and its central portion need not be so heavily braced with respect to its central vertical shaft portion and the journal for the latter. In addition, by using this construction with the previously described brace or securing means between the filling table and superstructure, the superstructure will be braced or secured directly from the base of the machine, rather than from the filling table alone. Such an arrangement is particularly desirable with filling structures of large diameter.

Other objects and advantages of the invention will be apparent from the following specification and accompanying drawings wherein:

25 Figure 1 is a horizontal sectional view of the filling structure of a filling machine, the filling reservoir being in horizontal section and the cover plate of the filling reservoir skirt being removed;

Figure 2 is a vertical sectional view on the line 2—2 of Figure 1;

30 Figure 3 is an enlarged view showing a portion of the Figure 2 structure, with parts in vertical section;

Figure 4 is a transverse sectional view on the line 4—4 of Figure 3;

35 Figure 5 is a vertical sectional view on the line 5—5 of Figure 1;

Figure 6 is a vertical sectional view on the line 6—6 of Figure 1; and

40 Figure 7 is a perspective view showing the filling table supporting structure.

Referring to Figure 2, the numeral 10 designates the filling table of a beverage filling machine, which table is supported in the usual fashion upon a hollow shaft 11 journalled for rotary movement upon an upstanding central hollow journal 8 fixed to the base 9 shown in Figure 7. Journal 8 surrounds a stationary vertically extending pipe 12 which delivers a liquid such as carbonated water or beer to the reservoir 13 of the filling machine. Reservoir 13 is supported upon a circular casting 14 including a flat skirt portion 15 substantially coextensive in diameter with the filling table 10. At its central portion, casting 14 includes a depending cylindrical skirt 16 which is braced by webs 17 and bears upon a sleeve 18 which surrounds the upper portion of the hollow shaft 11.

Sleeve 18 includes a vertical recess 19 in which a key 20 is mounted, the key engaging a key-way 21 in hollow shaft 11 so that the sleeve 18, and thereby the casting 14 and reservoir 13, will rotate with the hollow shaft. Key 20 is secured to a pin 22 mounted in a collar 23 threaded in sleeve 18. A head 24 at the outer end of the pin is engaged by the outer end of collar 23 and the inner end of the collar bears on key 20. It will be noted from Figure 2 that the recess 19 is of insufficient depth radially of sleeve 18 to permit key 20 to be drawn entirely from key-way 21. Thus key 20 can be disengaged from locking frictional contact with shaft 11 to permit sleeve 18 to be moved vertically by outward threaded movement of collar 23 but key 20 cannot be entirely withdrawn from key-way 21. Inward threading

of collar 23 will clamp key 20 in key-way 21 to assure a rigid central driving connection between shaft 11 and sleeve 18 and collar 23 can be locked in position by locking nut 23a.

The liquid supply pipe 12 extends into the reservoir 13 through a packed joint slidably upon the pipe during any vertical movement of the reservoir and casting 14.

As is usual with beverage filling machines, the casting 14 supports on its periphery a number of filling heads 25 corresponding in number to the bottle supporting platforms 26 which are mounted in the peripheral portion of the filling table 10 for vertical reciprocation to lift containers to a sealed position with respect to the filling heads. Each filling head 25 has a liquid tube 27 extending from its inner portion to the extreme lower portion of the filling reservoir 13 and a counter-pressure gas or air passage 28 extends from each filling head to the upper portion of the filling reservoir 13. This structure comprises the reservoir and filling head assembly or superstructure.

The lifting of containers to sealed position against the filling heads exerts an upward pressure upon the superstructure and a simultaneous downward pressure upon the filling table, the pressure being entirely at the peripheries of both elements, but never being exerted throughout the entire periphery because some container platforms will always be lowered to receive containers, as is the usual practice. The area not under vertical pressure is constantly changing as the filling structure rotates, which increases the tendency toward tilting.

In order that the filling heads 25 may be vertically adjusted with respect to the filling table 10 to enable the machine to handle containers of different heights, it is necessary to raise or lower the filling reservoir 13 and the casting 14 and, by the present invention, this is accomplished by means of jacks generally designated by the numeral 30 extending between the filling table 10 and the casting 14. As best shown in Figure 1, three such jacks are preferably provided, they being spaced a substantial distance from the axis or vertical centerline of the table 10 and reservoir 13.

Each jack comprises a sleeve 31 fixed to the table 10 and having its bore threaded as indicated at 32 to receive a threaded shaft 33 which is journaled in a hollow boss formed in the skirt 14. A tubular sleeve 35 preferably extends downwardly from the skirt 14 and encases the upper portion of the fixed sleeve 31 to surround the threaded shaft 33.

As best shown in Figure 1, each threaded shaft 33 is provided with a sprocket wheel engaged by a sprocket chain 30a and one of the shafts is provided with a gear mechanism generally designated by the numeral 40 and best shown in Figures 2 and 3 to enable the sprocket chain to be driven by an operator so that the three sprockets can be simultaneously rotated to thereby rotate the threaded shafts 33. In detail, the mechanism comprises a sprocket wheel 41 including a sleeved hub 42 provided on two of the threaded shafts 33, as shown in Figure 5. The third shaft 33 (Figure 2) also carries a sprocket wheel 41 at its upper end and with a beveled pinion 43 fixed thereto. Pinion 43 is engaged by a beveled gear 44 fixed to a horizontal shaft 45 extending radially of the skirt 14 and journaled in a bracket 46 secured to the upper surface of skirt 14.

As best shown in Figure 3, shaft 45 is squared at its outer end as indicated at 47 to receive an 75

operating crank or handle which can be fitted upon the portion 47 after removal of a cap 48 removably held in any suitable manner in an aperture formed in the cover plate 14a.

5 In order that shaft 45 will be held against rotation, a collar 50 is slidably mounted thereon, the collar having a square aperture which fits the squared portion 47 of shaft 45 so that the collar will be locked against rotation with respect to the shaft. Collar 50 includes a flange 52 having one or more pins 53 extending outwardly therefrom and a spring 54 in contact with a shoulder 55 on shaft 45 holds the collar 50 in the position illustrated in Figure 3 so that pin 53 will engage one of a series of apertures 56 formed in a housing 58 fixed to the bracket 46. Obviously, when a crank handle is applied to the squared portion 47 of shaft 45, collar 50 can be moved inwardly or to the right in Figure 3 so as to release the pin 53 from the position there illustrated and shaft 45 can then be rotated as desired to drive the three threaded shafts 33.

25 As best shown in Figure 1, the sprocket chain moves above strips or plates 59 suitably fixed upon blocks, not shown, provided on the upper surface of the skirt 14, the blocks being of sufficient height that the strips will be above the series of tubes 27 and 28 which connect the reservoir 13 with the filling heads 25. The sprocket chain is thus prevented from coming in contact with the tubes 27 and 28. As is also shown in Figure 1, it is necessary to slightly offset portions of the tubes 27 and 28 which are adjacent the sprocket wheels 30.

30 In order that the sprocket chain may be maintained at the proper tension, a take-up device generally designated by the numeral 60 is provided, the detail structure of this device being best shown in Figure 7. Referring to Figure 7, the take-up device 60 comprises a stub shaft 61 journaled in a flanged collar 62 which extends through an aperture 63 in the skirt 14, the collar being secured to the skirt by bolts such as indicated at 64 and extending through a flange 65 at the lower end of the collar. In addition, flange 65 has a pin 66 threaded therein, which pin extends through an arcuate slot 67 formed in the inner portion of a lever 68 keyed to the shaft 61. Pin 66 carries a nut at its lower end to enable the lever 68 to be locked in any adjusted position with respect to the pin.

55 At its upper end the stub shaft 61 carries a radially extending bracket 70 having a small sprocket 71 journaled thereon and which sprocket is adapted to bear upon and engage the sprocket chain. It will be obvious that the sprocket chain can thereby be held under the proper tension to enable the sprocket wheels 41 to be accurately simultaneously rotated.

60 In the operation of the above mechanism, if it is desired to raise or lower the skirt 14, reservoir 13, and filling heads 25 with respect to the filling table 10, it is only necessary to slightly withdraw the key 20 from close engagement with sleeve 18 of hollow shaft 11 so as to prevent any frictional drag against vertical movement at this point. Then an operating handle can be applied to the squared portion 47 of shaft 45 to rotate that shaft and, through the beveled gearing shown in Figure 3, simultaneously rotate the sprocket wheels 41 by the sprocket chain. This will cause the threaded shafts 33 to be rotated with respect to their respective sleeves 31 so that the desired raising or lowering can be accomplished.

The threaded connection between the shafts 33 and sleeves 31 is sufficiently close that there will be no play between these elements and rocking or tilting of the skirt 14 and the structures fixed thereto with respect to the filling table 10 will thereby be prevented. Also, the provision of the threaded jack structures 30 will prevent the skirt 14 from being lifted with respect to the table 10 by pressure of gas within the reservoir 13, thereby assuring that all containers will be properly positioned with respect to the filling heads.

In addition, the connection between the threaded shafts 33 and sleeves 31 is sufficiently close that, with the tight engagement of key 20 with central shaft 11, rotary movement will be imparted to the superstructure without possibility of any twisting moment.

It will also be noted that a rigidly acting connection between the filling table and superstructure is provided at spaced points in that each jack acts to positively lift and lower the adjacent portion of the superstructure.

Referring to Figure 2, it will be observed that the filling table 10 has a circular track or wear plate 80 fixed to its under surface near its edge and that this track bears upon rollers 81 journaled in the upper ends of standards 82 fixed to the base 9. The lower portions of the rollers 81 preferably move in cups 83 formed integral with the standards 82, the cups containing oil or grease which will be applied to the surfaces of the rollers to lubricate the track or wear plate 80.

By the arrangement shown in Figure 7, a filling table of even exceptionally large diameter can be securely held against all tilting and with a much lighter central or journal-engaging portion than is now provided with smaller machines. In addition, when the Figure 7 structure is used with the above-described means for bracing and securing the superstructure, the superstructure cannot tilt either with respect to the base 9 or the filling table 10 because a rigid structure is, in effect, provided between the base and the superstructure. Therefore, the Figure 7 structure, by preventing tilting of the filling table, further prevents tilting of the superstructure.

Provision against tilting and twisting of the superstructure is particularly important in present-day large capacity filling machines which may include a superstructure, i.e., a skirt 14, with its reservoir and filling heads, which is from five to ten feet in diameter and with a substantial portion of its weight at its periphery, due to the weight of the filling heads. With a superstructure of such diameter, the jacks would be positioned approximately two-thirds of the radial distance to the periphery, thereby giving support at points close to the periphery.

Also, since the filling table is essentially intended to support the superstructure against tilting by use of the jacks 30, it is highly desirable to, in turn, brace the filling table against tilting and to enable its central journal engaging structure to be of less weight.

The terminology used in the specification is for the purpose of description and not of limitation, the scope of the invention being indicated in the claims.

I claim:

1. In a supporting structure for a machine including a base, a vertical and rotatable shaft projecting upwardly from the base, and a pair of elements of relatively large diameter mounted on the shaft in superposed relation, means to adjust the vertical position of the upper element with respect to the lower of said two elements and to prevent the upper element from being tilted, said means comprising a plurality of threaded jacks connecting said elements and circumferentially spaced about said shaft at a substantial distance radially from the latter, and centrally positioned releasable means to secure said upper element in a rigid driving relation to said lower element.

2. In a supporting structure for a machine including a base, a vertical and rotatable shaft projecting upwardly from the base, and a pair of elements of relatively large diameter mounted on the shaft in superposed relation, means to adjust the vertical position of the upper element with respect to the lower of said two elements and to prevent the upper element from being tilted, said means comprising a plurality of threaded jacks connecting said elements and circumferentially spaced about said shaft at a substantial distance radially from the latter, means to simultaneously rotate said jacks, and centrally positioned releasable means to secure said upper element in a rigid driving relation to said lower element.

3. In a supporting structure for a machine including a base, a vertical and rotatable shaft projecting upwardly from the base, and a pair of elements of relatively large diameter mounted on the shaft in superposed relation, means to adjust the vertical position of the upper element with respect to the lower of said two elements and to prevent the upper element from being tilted, said means comprising a plurality of threaded jacks connecting said elements and circumferentially spaced about said shaft at a substantial distance radially from the latter, means to simultaneously rotate said jacks, and means to lock said last-named means against movement.

ROBERT J. STEWART.
